[57] CLAIM

The ornamental design of a butane powered soldering iron, as shown.

DESCRIPTION

FIG. 1 is a left side elevational view of a butane powered soldering iron showing our new design, the right being a mirror image thereof;

FIG. 2 is a bottom plan view;

FIG. 3 is a top plan view;

FIG. 4 is a front elevational view; and

FIG. 5 is a rear elevational view thereof.

FIG. 1

FIG. 2

FIG. 3

FIG. 4

FIG. 5
